UNITED STATES PATENT OFFICE

ALBERT D'AYRENX, CASIMIR CÉPÈDE, AND LOUIS RATORÉ, OF PARIS, FRANCE

DESIGN FOR AN ASEPTIC TOOTHBRUSH

Application filed July 12, 1930. Serial No. 36,340. Term of patent 3½ years.

To all whom it may concern:

Be it known that we, ALBERT D'AYRENX, CASIMIR CÉPÈDE, and LOUIS RATORÉ, citizens of France, residing at Paris, Republic of France, have invented a new, original, and ornamental Design for an Aseptic Tooth Brush, of which the following is a specification, reference being had to the accompanying drawings, forming part thereof.

Fig. 1 is a side elevation of an aseptic tooth brush, showing our new design; and
Fig. 2 is a rear elevation of the same.

We claim:

The ornamental design for an aseptic tooth brush, as shown.

LOUIS RATORÉ.

ALBERT D'AYRENX.

CASIMIR CÉPÈDE.
